Term of patent 14 years

(Cl. D49—1)

FIG. 3

The essential features of the design reside in the portions shown in full lines.

I claim:

The ornamental design for a laundry machine cabinet or similar article, as shown and described.
